BURNER CONTROL

Roy W. Johnson, Milwaukee, Wis.

Application November 30, 1939, Serial No. 306,905

11 Claims.

(CL. 236—1)

This invention relates to an improvement in controls, especially designed and adapted for use with heaters of the type wherein the heater is fired by a liquid fuel or oil burner.

A typical installation is in connection with a hot air furnace employing a pot type burner, or its equivalent, to which oil or liquid fuel is fed by gravity under the control of the metering valve. Air to support combustion is fed to the combustion chamber, usually by means of an electric motor-driven fan.

One of the objects of the present invention is to provide a control of this character, which exercises very effective regulation over the operation of the burner, in that it provides for a three stage burner operation, the metering valve being positioned under the automatic regulation of the control in either low fire or pilot position, or in a position to provide for a moderate or intermediate flame, or in position for a high or maximum fire flame. The control is responsive in its action to the regulation of a room thermostat, and it not only meters the flow of the liquid fuel to the burner, but also provides a means for coordinating therewith the control for the supply of air to the combustion chamber. In carrying out this purpose, the control regulates the operation of the electric motor which drives the pot fan, and also has a movable lever arm adapted to be connected to and to provide controlled motion for draft regulating dampers.

A still further object of the invention is to provide a control having these advantages and capacities, and which is very simple and compact in its construction, reliable and effective in operation, and easy and comparatively inexpensive to manufacture and install.

Other objects and advantages reside in certain novel features of the construction, arrangement, and combination of parts which will be hereinafter more fully described and particularly pointed out in the appended claims, reference being had to the accompanying drawings forming a part of this specification, and in which:

Figure 1 is a view partly in side elevation and partly in longitudinal and vertical cross section, showing a control device embodying the present invention.

Figure 2 is a fragmentary view taken in transverse vertical cross section on line 2—2 of Figure 4.

Figure 3 is a fragmentary view in vertical cross section, illustrating the metering valve, its high fire stop, and associated structure.

Figure 4 is a view of the oil control in top plan

5 with the shell-like cover of the control casing removed.

Figure 5 is a fragmentary view partly in side elevation and partly in longitudinal vertical section, showing the opposite side of the control from that illustrated in Figure 1.

Figure 6 is a view in horizontal cross section, taken on line 6—6 of Figure 5.

Figure 7 is a view in transverse vertical cross section, taken on line 7—7 of Figure 6.

Figure 8 is a fragmentary view in longitudinal vertical cross section, taken on line 8—8 of Figure 6.

Figure 9 is a view in elevation illustrating the manner in which the valve-operating lever is interlinked with the damper in the air supply conduit; and

Figure 10 is a diagram of the electrical circuits of the control.

Referring to the drawings, it will be seen that the furnace control device embodying the present invention comprises a main casing 10 having a main liquid supply chamber 11 therein. Liquid fuel is supplied to the chamber 11, and a constant level is maintained therein by mechanism which forms per se no part of the present invention, and which is fully disclosed in United States Letters Patent No. 2,068,138, granted January 19, 1937, to Roy W. Johnson. The liquid supply chamber 11 is provided with one or more outlets 13 (see Figure 3) which lead to the burner. The burner is usually of the pot type, and is not shown. The flow of liquid through each of the outlets 13 is regulated by means of a tubular metering valve 14 mounted for rectilinear up and down movement in a tubular valve guide 15, biased to open position by means of a spring 16, and further guided by a radially projecting pin 17, which works in a vertical guide slot in the guide tube 15. The construction of this metering valve 14, and also of its high fire stop 19 and low fire stop 20, except in the particulars which will be hereinafter described, is fully disclosed and claimed in the application 40 of Roy W. Johnson, for Interchangeable metering valve control, filed June 23, 1938, Serial No. 215,336, issued June 3, 1941, as Patent No. 2,244,161.

The upper end of the metering valve 14 projects up through an opening provided in the cover frame 10' of the casing 10, and also through an opening provided therefor in the base plate 21 of the casing of the control mechanism. The base plate 21 is fastened in position on the cover frame of the main casing. A control cover 22

of shell-like form coacts with the base plate 21, and with the uprights 15 integrally formed with the ends of the base 21, to complete the enclosure of the control parts. Screws or other suitable fastening devices are employed for securing the base plate 21 in position, and for releasably securing the control casing cover 22 assembled with the base plate 21.

A pair of transversely spaced vertical bracket plates 25 are integrally formed with the base plate 21 adjacent one end thereof. A valve-operating lever 26, which may be constituted of sheet metal, is formed at one end with a pair of spaced and apertured ears 27. A pivot pin 28, supported on the bracket plates 25, extends through apertures of the ears 27 to pivotally support or fulcrum the valve-operating lever 26 at one of its ends. The end of the lever 26 opposite its fulcrum is formed with a lateral extension 26', which overlies the upper end of the metering valve 14, and also overlies the low fire stop 20, so that when the lever 26 is allowed to swing downwardly, its extension 26' presses against a boss 14' formed on the upper end of the metering valve 14, and so causes the metering valve to move or shift to low or pilot fire position against the action of its spring 16. When the lever 26 has shifted the valve 13 to low fire position, the lever comes into engagement with the low fire stop 20, and any further downward movement of the lever 26 is prevented. A torsion coil spring 24 encircles a portion of the pivot in 28 located between the ears 27 of the valve-operating lever 26, and has extended ends 24', one end 24' bearing down upon the valve-operating lever, and the other end abutting the base plate 21. The spring 24 is thus tensioned to swing the end of the valve-operating lever 26, engageable with metering valve 14, downwardly. The torsion spring 24 is stronger than the valve spring 16 so that when the torsion spring 24 is free to act, it overcomes the effect of the spring 16.

The present invention proposes to provide a plurality of electric power elements to impart opening movement to the valve-operating lever 26, and proposes to energize and deenergize the power elements under control of the room thermostat, so that depending upon the demands of the room thermostat the valve 14 will occupy either high or low, or intermediate fire position.

The electric power element, which is employed for shifting the valve-operating lever to an intermediate fire position, takes the form of a bimetallic leaf, designated at 29. The leaf 29 has one end fastened, as by screws 29', to a bearing pad 25' provided therefor on the base 21. The opposite end of the leaf 29 underlies an angular lug 30, which is formed integral with the valve-operating lever 26. An electric heating element 31 is clipped, or otherwise suitably secured, to the underside of an intermediate portion of the bimetallic leaf 29, and when it is energized, and heats up, it causes the leaf 29 to flex upwardly. The free end of the leaf 29 when so flexed presses up against the underside of a bearing button 30' fixed to the horizontal portion of the angular lug 30, and consequently shifts the valve-operating lever 26 upwardly, and does this to such extent as to permit the valve spring 16 to move the valve to intermediate fire position. A stop screw 32 is mounted on the base plate, and is arranged so that a portion of its head overlies the free end of the bimetallic leaf, and will engage such end of the leaf and arrest further upward movement thereof when the valve-operating lever, and con-

sequently the metering valve 14, are in intermediate fire position.

For the purpose of shifting the valve-operating lever 26, and consequently the metering valve 14, to high fire position, the invention proposes an electro-power element in the form of a bellows or expansible chamber 35. The cylindrical casing of the bellows 35 is fixedly supported on a bellows bracket 41 which is in turn secured to the bracket plates 25 and the base 21. The vertical portion of bellows bracket 41 has an opening in which one end portion of the cylindrical casing of the bellows is fitted, and such end portion of the bellows casing has an integral outwardly directed annular flange 35' which overlaps the margin of the opening in the bellows bracket 41 and is secured thereto by screws 42 (see Figures 2, 6, and 7). A washer 43 is interposed between the flange 35' and bellows bracket 41. The bellows 35 is filled with an expansible liquid or fluid. An electric heating element 36 energized and de-energized under the influence of the room thermostat, and, acting when energized to cause the fluid in the bellows to expand, surrounds the metal casing of the bellows. The electric heating element is preferably in the form of a fine wire of zigzag form embedded in thin sheets of mica which are wrapped around and clamped snugly up against the outer wall of its bellows casing. When the fluid in the bellows 35 is expanded its bellows tip 37 moves outwardly, and due to its engagement with the bearing screw 38 of bell-crank lever 39 rocks the bell-crank lever in a counter-clockwise direction, as viewed in Figure 8. The lever 39 is also pivotally mounted on the pivot pin 28 alongside of the lever 26, and its lower arm 39' is flat and curved laterally and underlies the valve lever 26. A torsion coil spring 40, which has its coils encircling a portion of the pin 28, has one end bearing against the base plate and its opposite end bearing down on the arm 39' of the lever 39, so as to swing the arm 39 downwardly away from the lever 26, except when the fluid in the bellows is expanded.

The bellows 35, when the fluid in it is expanded, acts through lever 39 to swing valve-operating lever 26 upwardly away from the valve 14 to such extent as to allow the valve spring 16 to move the valve 14 to full open or high fire position. High fire stop 19 engages valve pin 17 to limit the extent to which valve 14 may open. The lever 26 is free to continue to travel upwardly away from the valve 14 after the valve is fully open, and this is desired in many instances. For example, it may be desired or required, where such movement of the valve-operating lever 26 is employed, to regulate the action of a damper for controlling the air supply to the burner.

However, while this over travel of the lever 26 away from the valve 14 is desirable in some instances, it is important that its return movement under the control of the bellows 35 be promptly transmitted to the valve 14 to effect its return to intermediate fire position while leaving the shifting of the valve 14 from intermediate fire position to low or pilot fire position under the complete control of the bimetallic leaf 29. To carry out these purposes and effect the action desired the valve-operating lever 26 not only has its extension 26' cooperable with the boss 14' of the metering valve 14, but also is interconnected therewith by a motion transmission train including frictionally interengaged elements, which, while capable of transmitting motion from the lever 26 to the valve 14, may slip or slide relative

to each other when required. Generally speaking, this motion transmission train includes a spring wire clip 60 positively interconnected with the lever 26 and a sliding friction sleeve 61 engageable with the upper end of the valve 14 and frictionally gripped by the clip 60.

The clip 60 is shaped, as shown to advantage in Figure 6, and has a pair of spring arms 60a and 60b integrally connected at one end by a bight portion. Adjacent its bight portion the 10 clip is frictionally and securely engaged in an annular groove provided in the upper end of the button 30 fastened to the angular lug 30 of the lever 26. Adjacent their free ends the spring 15 arms 60a and 60b straddle and frictionally engage the friction sleeve 61.

The friction sleeve 61 overlies a portion of the upper end of the valve 14 to one side of the boss 14' and extension 26' of the lever 26, and it may be conveniently constrained to vertical sliding 20 movement by slidably fitting it on a manually operable shut-off pin 62 with which the control is also provided.

The portion of the friction sleeve 61 which the clip 60 engages is constituted to frictionally engage the clip 60 and yet at the proper time permit the desired slippage of the clip along such portion of the sleeve, but the lower end of the sleeve 61 (which is not engaged by the clip 60 at any time) is externally threaded. An internally threaded stop disk 63 is threadedly engaged with the lower portion of the sleeve so as to be adjustable therewith. The stop disk 63 is adjusted at the factory, and to preclude tampering with the adjustment in the field, it may be permanently secured in its final adjustment by soldering.

A snap ring 60' is snapped into an annular groove provided in the upper end of the sleeve 61 to prevent the arms 60a and 60b of the clip 60 from riding off the upper end of the sleeve 61.

The shut-off pin 62 is supported by means of a two-part casing or cylinder 64 suitably mounted on the terminal board 45. The sections of the casing 64 are threadedly interconnected and held in any selected adjustment by a friction spring 64'. A spring 62' encircles the pin 62 within the casing 64, and has its lower end abutting the lower section of the casing 64 and its upper end abutting a collar 62a integral with pin 62. A button 62b integral with the pin 62 projects above the casing 64. When the button 62b is depressed the shut-off pin moves downwardly against the action of spring 62' to punch the metering valve 14 to fully closed or shut-off position.

With this construction when the bellows 35 is heated up, and the lever 39 swings lever 26 upwardly, the valve 14, levers 26 and 29, wire clip 60, and sleeve 61 all move upwardly together until the valve 14 reaches high fire position whereupon its further upward movement is arrested by high fire stop 19. At about the same time the upper end of the sleeve 61 engages the lower end of casing 64, and its further upward movement is stopped. The levers 39 and 26 and wire clip 60 may continue to move upwardly, the wire clip 60 slipping along the friction sleeve 61. But when the electric heating element 36 is de-energized, and the bellows cools off, and levers 39 and 26 start to swing back toward the valve 14, the wire clip 60 at once moves the sleeve 61 downwardly, and as its lower end is engaged with the valve 14 the valve is also moved toward its seat until it comes to intermediate fire position,

5 at which time the stop disk 63 of the sleeve 61 engages the top of stop screw 32 to arrest further downward movement of the disk 63 and its sleeve 61. The lever 39 may then continue to move downwardly, and the bimetallic leaf 29 takes over the control of lever 26, and if the leaf 29 permits further downward movement of lever 26 then clip 60 slips downwardly on the friction sleeve 61.

10 The terminal board 45 is of Bakelite or other insulating material, and of general plate-like form, and is supported in the control casing on the bracket plates 25 and on vertical posts 46 provided therefor. Screws 47 secure one end of the terminal board to the posts. The opposite end of the terminal board has a depending lug-like and integral extension 48, which rests on the horizontal flange of the bellows bracket 41, and is fastened in position by screws 49, which also secure the bellows bracket 41 to plates 25.

15 A mercury switch 50 is provided for controlling the operation of the electric motor for the pot fan or the fan that supplies air to the combustion chamber. The glass envelope of this switch is supported in a clip 51 carried at the outer end of a short rock arm 52. The other end of this rock arm 52 is pivotally mounted on a pivot pin 53 supported in a sleeve-like bearing formed integral with the under side of the terminal board. The switch is interlocked with the control mechanism for the metering valve 14 so that it will be in its open position when the metering valve is in low fire or pilot position, or will be closed in the other positions of the valve. For 20 this purpose, and for other purposes which will be hereinafter described, the valve-operating lever 26 has an extension 56 spot-welded thereto. A vertical lug 57 is formed integral with this extension, and is pivotally connected to the lower 25 end of a link 58.

25 The upper end of the link 58 is provided with a slot 58'. A headed pin 52' extends through this slot 58' and is fastened to rock arm 52 to provide a lost motion connection between the upper end of the link 58 and the rock arm 52. A mousetrap spring 59 is interposed between the link 58 and rock arm 52, and has the arms diverging from its coiled bight portion secured respectively to the link 58 and rock arm 52.

30 The upward swinging movement of the mercury switch 50 is limited by the terminal board 45, and since the valve-operating lever 26 partakes of considerable swing, it is practically necessary to provide some means to allow the lever 35 26 to continue to swing after the mercury switch 50 has been tilted to closed position, and this necessity is very advantageously satisfied by the pin and slot connection 52', 58', and the spring 59.

35 50 When either the bi-metallic leaf 29 or bellows-actuated lever 39 swing the valve-operating lever 26 upwardly, the link 58 is thrust upwardly and the spring 59 transmits the upward movement of the link 58 to the rock arm 52 to tilt the mercury switch to closed position. If the lever 26 continues to move upwardly, the spring 59 yields and the link 58 shifts relative to the rock arm 52, the slot 58' of the link 58 sliding along the pin 52' to permit this relative movement.

40 55 60 Field adjustments of the high and low fire stops are facilitated by the provision of an extension operating rod 67 of the high fire stop, and of an extension operating wire 68 of the low fire stop, both of these operating elements 65 70 being accessible through the top of the terminal 75

board when the control casing cover is removed.

While any suitable room thermostat may be utilized to regulate the energization of the electric heating elements 31 and 36, I prefer to use a room thermostat of the type diagrammatically illustrated in Figure 10, and wherein the movable (white) contact is disengaged from both the so-called red and blue fixed contacts when the bi-metallic element controlling the movable contact means occupies the position in which the room thermostat is satisfied.

In the diagrammatic illustration in Figure 10, the room thermostat 70 is shown as having the red, white, and blue contacts 71, 72, and 73. White contact 73 is connected by wire 74 with binding post numbered 1 on the terminal board 45; red contact 71 is connected by wire 75 with binding post numbered 2 on board 45; and blue contact 72 is connected by wire 76 with binding post numbered 4. The bi-metallic element 70' of the room thermostat carries the movable contact 71' cooperable with red contact 71, and also has an insulating button 70a engageable with the movable blade contact 73' mounted on and electrically connected with the white contact 73 and biased to engage an extension 72' of blue contact 72. A flexible conductor 73a also electrically connects the bi-metallic element 70' and its movable contact 71' with the white contact 73.

Wire 77 connects binding post numbered 4 with one terminal of the heating element 31 of the bi-metallic leaf 29. The other terminal of element 31 is connected by wire 78 to binding post numbered 3. Wire 79 connects binding post numbered 2 with one terminal of bellows heater 36. The other terminal of the heater 36 is connected by wires 80 and 78 to the binding post numbered 3.

The low voltage circuits of the control device are energized from the line through a step down transformer shown diagrammatically at 81, one of the terminals of the secondary coil of transformer 81 being connected by wire 82 to binding post 1, and the other by wire 83 to binding post 3.

In Figure 10 the pot fan motor, which supplies air to the pot or combustion chamber of the burner, is designated diagrammatically at 85. One terminal of the motor is connected directly to one side of the line by wire 86. The other terminal of the motor is connected by wire 87 to binding post 8 of the terminal board. Wire 88 connects binding post 8 to one of the electrodes of the mercury switch 50. The other electrode of this mercury switch 50 is connected by wire 89 to binding post 7, which in turn connects by wire 90 to the other side of the line. It is obvious that when the body of mercury in the mercury switch bridges the electrodes, the circuit through the pot fan motor is completed, and that when the mercury switch is tilted to leave a gap between the electrodes, the circuit through the pot fan motor is broken.

When the bi-metallic element 70' of the room thermostat 70 is in the position shown in Figure 10, then the room thermostat 70 is satisfied and the circuit through both the heaters 31 and 36 is broken, and both are de-energized so that the metering valve is in its pilot or low fire position. If the temperature conditions to which the room thermostat 70 is subjected are such to cause the bi-metallic element 70' to move toward the left, as viewed in Figure 10, then the movable blade contact 73' will engage the extension contact 72' of blue contact 72 and current will flow from one

terminal of the secondary of the transformer 81, through wire 82, binding post 1, wire 74, white contact 73, movable blade contact 73', extension contact 72', blue contact 72, wire 76, binding post 4, wire 77, electric heating element 31, wire 78, binding post 3, and wire 83, back to the other terminal of the secondary of the transformer. As the heating element 31 heats up, it flexes its thermostatic leaf 29 upwardly to raise the metering valve to intermediate fire position.

If the temperature conditions in the environment of the room thermostat are such as to cause its bi-metallic element 70' to continue to move to the left until its movable contact 71' engages the red contact 71, then the current will flow from one terminal of the secondary of the transformer 81, through wire 82, binding post 1, wire 74, white contact 73, flexible conductor 73a, bi-metallic element 70', movable contact 71', red contact 71, wire 75, binding post 2, wire 79, electric heating element 36 of bellows 35, wire 80, and wire 78 to binding post 3, and then through wire 83 to the other terminal of the secondary of the transformer. The heater 36 heats up the expansible or volatile fluid or liquid in the bellows 35, and thereby shifts the lever 39 to further raise the valve-operating levers 26 and allow the valve 14 to fully open or come to high fire position.

As previously indicated, supply of air to the combustion chamber is regulated or coordinated with the supply of fuel to the burner, and for this purpose the extension 56 of the valve-operating lever projects out beyond the control casing, and has a yieldable connection consisting of a spring 91 and nut 92 to the upper end of a rod 93. The lower end of this rod extends through an opening provided therefor in the short arm of a lever 94. The details of the damper form no part of this invention and are more fully described and claimed in United States Patent No. 2,251,055, issued July 29, 1941, on application of David J. Howard and Samson J. Johnson. Below the short arm of the lever a washer 95 and cotter pin 96 are combined with the rod to provide an abutment for bearing points 97 formed in the short arm of the lever. A spring 98 bears down on the short arm of the lever and abuts a collar 99 on the rod. This structure provides a desirable type of yieldable operable connection between the rod and the lever 94. The lever 94 is pivoted or fulcrumed as at 100 on a mounting bracket 101 supported on the conduit 102 between the fan and the pot or combustion chamber of the burner. This conduit 102 has an opening 104 in its under side. Supported for rotation on the conduit, and in controlling relation to the opening 104, is a damper 105. The damper is fixed on a rotatably supporting shaft 106 mounted in any suitable way on the conduit 102. A crank arm 107 is secured by a set screw 108 to the shaft 106. The outer end of this crank arm is pivotally connected to the lower end of the link 109, and the opposite end of this link is pivotally connected to the outer end of the long arm of the lever 94. With this or some equivalent system of linkage and leverage, the motion of the valve-operating lever, or of its extension, is multiplied sufficiently to give a different position to the damper for each position of the metering valve. When the metering valve is in its pilot or low fire position, the damper is positioned in the full line shown in Figure 10, blocking the passage through conduit from the fan to the burner but allowing a natural draft from the atmosphere through a portion of the opening 104 to the combustion

chamber. When the metering valve is in an intermediate firing position, the damper 105 is angled so as to partially block conduit 102. However, when the metering valve is in its high firing position, the damper 105 closes the opening 104 and leaves the conduit 102 unobstructed so that the entire draft set up by the fan is delivered to the combustion chamber.

While I have shown and described one construction in which the invention may be advantageously embodied, it is to be understood that the construction shown has been selected merely for the purpose of illustration or example, and that various changes in the size, shape, and arrangement of parts may be made without departing from the spirit of the invention or the scope of the subjoined claims.

I claim:

1. A control for oil burners comprising a metering valve biased to open position and regulating the flow of fuel to the burner, a valve-operating lever engageable with the valve to move it toward closed position when swung in one direction and to allow it to open when swung in the opposite direction, a bi-metallic leaf flexing when heated to swing the lever in a direction to allow the valve to open, means for limiting the extent to which said leaf may flex when heated, an electric heating element for heating the leaf, a bellows having an expansible fluid therein, a connection between the bellows and said lever operable when the fluid in the bellows is heated to swing the lever farther away from the valve, an electric element for heating the fluid in the bellows, and thermostatic means for regulating the energization and de-energization of said electric heating elements.

2. A control for oil burners comprising a metering valve biased to open position and regulating the flow of oil to the burner, a main valve-operating lever having one end fulcrumed and having its other end overlying the metering valve and acting when swung in one direction to force the valve toward closed position, and when swung in the other direction to allow the valve to open, a thermostatic leaf flexed when heated and engageable with the lever to shift the lever in a direction to allow the valve to open, an electric heating element for said thermostatic leaf, means for limiting the extent to which said leaf may flex under the influence of heat, a bellows containing an expansible fluid and having a bellows tip moved outwardly when the fluid is heated, an auxiliary valve-operating lever engaged by said bellows tip and having an arm underlying the main operating lever and engageable therewith to shift the same farther away from the valve, an electric heating element surrounding the bellows, and a room thermostat for controlling the energization of said electric heating elements.

3. A control for oil burners comprising a metering valve biased to open position and regulating the flow of fluid to the burner, a main valve-operating lever overlying the valve and engageable therewith to move the valve toward closed position when swung in one direction and to allow the valve to open when swung in the other direction, said lever having an angular lug projecting from one side thereof, a bi-metallic leaf flexed when heated and engageable with said lug to move the lever away from the valve, an electric heating element for said bi-metallic leaf, a stop for limiting the extent to which the leaf may flex, an auxiliary valve operating lever having an arm underlying the main operating

lever and effective when swung in one direction to move the main valve operating lever to a position to allow the valve to fully open, a bellows containing an expansible fluid and having a bellows tip engageable with the auxiliary valve-operating lever, an electric heating element for heating the fluid in the bellows, and thermostatic means for regulating the energization of said heating elements.

4. A control for oil burners comprising a metering valve for regulating the flow of fuel to the burner, said metering valve being biased to open position, a valve operating lever engageable with the valve to move it toward closed position when swung in one direction and to allow it to open when swung in the opposite direction, a bi-metallic leaf operable when heated to swing the lever in a direction to allow the valve to open, adjustable means for limiting the extent to which the leaf may flex when heated while permitting the lever to further swing in said direction, an electric heating element for heating the leaf, and thermostatic means for regulating the energization and de-energization of said electric heating element.

5. A control for oil burners comprising a metering valve biased to open position and regulating the flow of fuel to the burner, a valve-operating lever overlying the valve and engageable therewith to move the valve toward closed position when swung in one direction and to allow the valve to open when swung in the other direction, an electro-responsive power element cooperable with the lever to move the same in the direction to allow the valve to open, a one-way friction drive between said lever and said valve operable to impart closing movement to the valve when the lever is swung in one direction, stop means to limit the extent to which said friction drive may move the valve toward closed position, and thermostatic means for controlling the action of said electro-responsive element.

6. A control for oil burners comprising a metering valve biased to open position and regulating the flow of fluid to the burner, a main valve-operating lever overlying the valve and engageable therewith to move the valve toward closed position when swung in one direction and to allow the valve to open when swung in the other direction, an auxiliary valve-operating lever having an arm underlying the main operating lever and effective when swung in one direction to move the main operating lever to a position to allow the valve to open, a bellows containing an expansible fluid and having a bellows tip engageable with another arm of said auxiliary arm operating lever, and thermostatic means for regulating the expansion and contraction of the fluid in said bellows.

7. A control for oil burners comprising a metering valve biased to open position and regulating the flow of fluid to the burner, a main valve-operating lever overlying the valve and engageable therewith to move the valve toward closed position when swung in one direction and to allow the valve to open when swung in the other direction, thermostatically controlled means cooperable with the lever for swinging the same in a direction to allow the valve to open, means for limiting the extent to which said thermostatically controlled means may swing the lever in a direction to allow the valve to open, an auxiliary valve-operating lever having an arm underlying the main valve-operating lever and effective when swung in one direction to move the

main valve-operating lever to a position to allow the valve to fully open, and thermostatically controlled means for actuating said auxiliary valve-operating lever.

8. A control for oil burners comprising a metering valve biased to open position and regulating the flow of oil to the burner, a high fire stop cooperable with the valve to limit the opening movement thereof, an operating lever overlying and engageable with the valve to move the valve toward closed position when swung in one direction and to allow the valve to open when swung in the other direction, a low fire stop underlying the lever and limiting the extent to which the lever may swing to close the valve, two electro-responsive power elements operatively connected with the lever for swinging the lever in a direction to allow the valve to open when said electro-responsive power elements are energized, means for limiting the extent to which one of said electro-responsive power elements may swing the lever whereby to cause the valve to occupy a position intermediate its high and low fire positions when said last named electro-responsive power element is energized, and thermostatically controlled means for regulating the energization of said electro-responsive power elements.

9. A control for oil burners comprising a metering valve biased to open position and regulating the flow of fuel to the burner, a valve-operating lever engageable with the valve to move it toward closed position when swung in one direction and to allow it to open when swung in the opposite direction, a bi-metallic leaf flexing when heated and co-acting with the lever to swing the lever in a direction to allow the valve to open, means for limiting the extent to which said leaf may flex when heated, an electric heating element for heating the leaf, a bellows having the expandible fluid therein, a connection between the bellows and said lever operable when the fluid in the bellows is heated to swing the lever farther away from the valve, a one-way friction drive between said lever and said valve operable to impart closing movement to the valve when the lever is swung toward the valve and including frictionally interengaged elements one connected to the lever and the other engageable with the valve, the element engageable with the valve also being engageable with said means to limit the extent to which it may move the valve toward closed position, and thermostatic means for regulating the energization and deenergization of said electric heating elements.

10. A control for oil burners of the type having an electric motor-driven fan for supplying air to the combustion chamber of the burner and a metering valve biased to open position and regulating the flow of oil to the burner and comprising a high fire stop cooperable with the valve to limit the opening movement thereof, an operating lever overlying and engageable with the valve to move the valve toward closed position when swung in one direction and to allow the valve to open when swung in the other direction, a low fire stop underlying the lever and limiting the extent to which the lever may swing to close the valve, an electrically energized power element cooperable with the lever to swing the same away from the low fire stop to allow the valve to open, a mercury switch for regulating the supply of electric current to said motor, a tiltable support for said switch, a link having one end pivotally connected with the lever, and a spring-tensioned lost motion connection between the other end of the link and the tiltable support.

11. A control for oil burners comprising a metering valve biased to open position and regulating the flow of oil to the burner, a high fire stop cooperable with the valve to limit the opening movement thereof, an operating lever overlying and engageable with the valve to move the valve toward closed position when swung in one direction and to allow the valve to open when swung in the other direction, a low fire stop underlying the lever and limiting the extent to which the lever may swing to close the valve, two electro-responsive power elements operatively connected with the lever for swinging the lever in a direction to allow the valve to open when said electro-responsive power elements are energized, means for limiting the extent to which one of said electro-responsive power elements may swing the lever whereby to cause the valve to occupy a position intermediate its high and low fire positions when said last named electro-responsive power element is energized, a one-way friction drive between said lever and said valve operable to impart closing movement to the valve when the lever is swung toward the valve and having its valve-engaging element cooperable with said means to limit the extent to which said friction drive may move the valve toward closed position, and thermostatically controlled means for regulating the energization of said electro-responsive power elements.

ROY W. JOHNSON.
